UNITED STATES PATENT OFFICE.

EDWARD E. KALLENBACH, OF ST. LOUIS, MISSOURI, ASSIGNOR TO PFEIFFER CHEMICAL COMPANY, OF ST. LOUIS, MISSOURI, A CORPORATION OF MISSOURI.

COUNTING AND RECEPTACLE-FILLING MACHINE.

937,152.

Specification of Letters Patent. Patented Oct. 19, 1909.

Application filed August 15, 1908. Serial No. 448,680.

To all whom it may concern:

Be it known that I, EDWARD E. KALLENBACH, a citizen of the United States, residing at the city of St. Louis, State of Missouri, have invented a certain new and useful Improvement in Counting and Receptacle-Filling Machines, of which the following is a specification, reference being had to the accompanying drawings, forming a part of this specification, in which—

Figure 1 is a top plan view of a counting and receptacle-filling machine embodying my invention; Fig. 2 is a side elevational view thereof; Fig. 3 is a front elevational view thereof; Fig. 4 is a cross-sectional view on the line 4—4, Fig. 1; Fig. 5 is a cross-sectional view on the line 5—5, Fig. 1; Fig. 6 is a detail plan view of the disk-carrying ring, showing the coöperative relation between the tappets carried thereby and the slide-actuating lever and the disk-revolution counting-wheel or dial; Fig. 7 is a horizontal sectional view on the line 7—7, Fig. 3; Fig. 8 is a detail view of the receptacle-shifting pawl or dog; Fig. 9 is a plan view of a counting and delivery disk for the tablets, pills, or the like; and Fig. 10 is a fragmentary view of a modified form of tablet or pill counting and delivery disk.

This invention relates to a new and useful improvement in counting and receptacle-filling machines, and more particularly to machines for counting tablets, pills, or the like, and filling receptacles with the same, the object being to provide a machine of the kind described by which the handling and counting of tablets, pills, and the like is facilitated and the filling or packing into receptacles of a predetermined number or quantity of such tablets, pills, and the like is easily and quickly accomplished.

With this object in view, my invention consists in the provision of means for handling and counting tablets, pills, and the like of different sizes or forms in the same machine; in the provision of means for delivering and filling into receptacles of a predetermined quantity or number of such tablets, pills, or the like; in the provision of means for intermittently feeding receptacles or packages into position to be filled with said tablets, pills, and the like; and in the novel construction, arrangement, and com-

bination of the several parts, all as will hereinafter be described and pointed out in the 55 claims.

In the drawings, 1 indicates a base, on which is mounted a frame comprising preferably a front-plate 2, a rear-plate 3, side or cross-pieces 4, and a top member or table 5. Upon table 5 is mounted a hopper 6, in which the tablets, pills, or the like are adapted to be placed preparatory to being counted and filled into the receptacles or bottles X.

Rotatably mounted on the bottom of hopper 6 is, what I term, a tablet-counting and delivering disk 7, which is provided near its margin and for the great part of its outer area, see particularly Fig. 9, with circular series of perforations or holes 7^a, but leaving along its margin a non-perforated section or portion 7^b. The disk 7 is arranged to project at one side, see particularly Figs. 1, 2, and 4, outside hopper 6 through an opening 8 in the front wall of hopper 6, so as to overlie an opening 9 in the front part 10 of table 5, for which opening 9 said non-perforated section 7^b of disk 7 is designed to act as a cover at a certain period of the revolution of said disk, and under which opening is 75 adjustably mounted a chute 11 for delivering the tablets, pills, or the like received in and carried by perforations 7^a in disk 7 into the receptacles or bottles X, as more fully 80 hereinabove described.

Disk 7 is mounted on or carried by a rotatable ring or gear 12, which has a hub portion 13 projecting through a central opening 14 in disk 7. Ring 12 has also on its upper surface, see particularly Fig. 4, a 90 stud or tappet 15 adapted to project through a small opening or pocket 7^c in disk 7, whereby said disk is revolved or rotated on the rotation of said ring 12.

Hub 13 is arranged on a supporting spin- 95 dle 16 having a base portion 17 arranged on a shelf 18 mounted on side-pieces 4 in the upper part of the frame of the machine and beneath the table 5. Ring 12 is provided on its under side with a circular beveled rack 100 19, which is adapted to mesh with a bevel pinion 20 secured on a shaft 21 journaled in said base portion 17; and in alinement with shaft 21 and on the opposite side of said base portion or frame 17 is journaled an 105 idler bevel pinion 22, which also meshes with

rack 19 and supports and balances said ring 12.

On the outer end of shaft 21 is mounted a pulley 23, which is belted down to a driving pulley 24 mounted on a counter-shaft 25 arranged on rear-plate 3 of the frame of the machine. Shaft 25 has also mounted thereon a pulley 26 adapted to be belted to an electric motor or other source of power 27. It will thus be obvious that, on the rotation of pulley 26, the disk 7, through the mechanism described, will be rotated to deliver through opening 9 into the receptacle X therebeneath the tablets, pills, or the like carried in the perforations 7a thereof.

Adjustably and detachably mounted on the front-plate 2, see particularly Fig. 4, is a bracket 28 having a supporting-arm 29 projecting forwardly therefrom and on which arm is arranged a work-table 30. The said bracket 28 has a slot-and-pin connection with said front-plate 2, whereby said bracket may be vertically adjusted on front-plate 2, or may be, together with the parts attached thereto or mounted thereon, entirely removed from the machine, for purposes hereinafter stated, said bracket 28 being secured to, and held in adjusted positions on, said front-plate 2 by means of the thumbscrew 31.

Extending around one end of table 30 is an endless feed-belt 32, which is adapted to carry the receptacles of bottles X inwardly to be filled. Belt 32 is carried at one side of table 30 by an idle roller 33 mounted in adjustable brackets 34 arranged on the under side of table 30. Brackets 34 have a slot-and-pin connection with the under side of table 30, whereby slack in belt 32 may be taken up whenever necessary, said brackets being held in adjusted positions by thumbscrews 35. At the inner side of the table 30, belt 32 is carried by a driving pulley 36 fixedly mounted on a shaft 37 journaled on the bracket 28. On the outer end of shaft 37 is fixed a pulley 38, which is belted to a pulley 39 mounted on the shaft 21, whereby, on the rotation of ring 12, by the mechanism heretofore described, belt 32 will be rotated around said pulleys 33 and 36 for feeding bottles X or other receptacles inwardly to be filled.

Adjustably mounted on table 30 adjacent to and parallel with feed-belt 32 is a guide-plate 40, and at the opposite side of said feed-belt and on said table 30 is adjustably mounted a plate 41, whose inner portion is widened and terminates some distance short of the front face of bracket 28, thereby providing a passage-way across the front of the machine and beneath chute 11 for the receptacles X to be filled, as shown particularly in Figs. 1 and 4. The plate 40 has preferably a slot-and-pin connection with the table 30 and is secured in adjusted positions by a

thumb-screw 42, said plate 40 being adjustable laterally with respect to table 30, so that, in connection with plate 41, the passage-way over said belt 32 may be regulated to fit different sized receptacles to be filled. The plate 41 is provided with an enlarged circular opening 43, over which is adapted to be placed a washer 44 having a central opening therein, whereby said washer may be placed over a threaded pin or stud 45 mounted in table 30, the plate 41 being held in adjusted positions on said table 30 by a thumb-screw 46 fitting on said pin 45. By this arrangement, the plate 41 is universally adjustable, so that not only may the passage-way for the receptacles over said belt be regulated, in connection with plate 40, but also the said passage-way across the front of the machine and beneath chute 11 may be regulated to accommodate different sized receptacles which it may be desired to fill with the tablets, pills, or the like, said receptacles being thus held in alignment and in proper position to be filled.

In the front face of bracket 28 is formed a groove or slide-way 47, which is preferably under-cut, so as to accommodate a beveled slide 48, on the rear side of which slide is mounted a stud or pin 49 projecting inwardly through an elongated slot 50 in bracket 28. The pin 49 is connected by a link 51 to a rocking-lever 52 pivotally mounted on front-plate 2. Slide 48 is normally held in its retracted position, as shown in dotted lines in Fig. 3, by a spring 53, this spring 53 being connected at one end to rocking-lever 52 and at its other end to the front-plate 2. The upper end of rocking-lever 52 has an inturned portion or projection 54, which is adapted to be struck by a tappet 55 on the periphery of disk-carrying wheel 12, see particularly Figs. 3 and 6, so that, once during every revolution of said ring 12, the rocking-lever 52 is rocked, thereby moving the slide 48 and the receptacle-shifting pawl or dog 56 across the front of the machine to shift or feed a receptacle or bottle X under the chute 11. The pawl or dog 56 is pivotally mounted near the end of slide 48 and has at its inner end a tail-piece 57 adapted to contact with preferably a rubber buffer 58 arranged in the end of slot 50 to throw the dog 56 outwardly perpendicular to the slide 48 when said slide is in its normal or retracted position, ready to engage and shift a receptacle or bottle X under chute 11 to be filled.

The chute 11 is preferably adjustably mounted on the under side of the forward portion 10 of table 5 by means of an angle-bracket 59. One arm of said bracket has preferably a slot-and-pin connection with chute 11, and the other arm of said bracket has preferably a slot-and-pin connection with portion 10 of table 5, whereby said

chute is not only adjustable vertically, but also laterally, with respect to said table 5, and may also be swung outwardly away from front-plate 2, the said chute being held 5 in adjusted positions by means of thumb-screws 60. Chute 11 is thus adjustable to accommodate different sized receptacles and to properly feed the tablets, pills, and the like thereto.

10 Adjustably mounted in the front wall of hopper 6 is a slide 61, which has a slot-and-pin connection therewith, the slide 61 being held in adjusted positions by means of a thumb-screw 62. This slide 61, when in its 15 lowered position, is adapted to nearly touch against disk 7, thus not only assisting to keep disk 7 in position on hub 13, but also closing opening 8 in the front wall of hopper 6, so as to prevent the escape of any tablets, pills, or other articles therein. It will 20 also be seen that the tablets, pills, or the like will be forced into proper position in perforations 7^a by said slide 61 before they can pass thereunder on the rotation of said 25 disk 7.

63 indicates what might be termed a deflector-plate, which is somewhat of a conical shape and is adapted to fit on the bottom of hopper 6 over the central part of disk 7, as 30 shown particularly in Fig. 5. Plate 63 is provided on its under side with a central bore 63^a adapted to fit hub 13 of ring 12 and is also provided on its under side with a circular groove 63^b to allow for the passage of 35 stud or tappet 15 on the rotation of ring 12 and disk 7. This plate 63 thus not only serves to cover the said hub 13, but also to deflect the tablets, pills, or the like outwardly on to disk 7 and into the perforations 40 7^a therein, this plate 63 being cut-away at one side, see Fig. 1, so as to fit closely up against slide 61, when said slide 61 is in its lowered position. As shown in dotted lines in Fig. 5, the deflector-plate 63 may be made of 45 various diameters, so as to regulate the capacity of disk 7 by covering part of the perforations 7^a therein, for purposes hereinafter stated.

From the above description, the operation 50 of my machine is clear. The tablets, pills, or the like are placed or put in the hopper 6, which is usually kept pretty well filled, the tablets, pills, or the like falling or being deflected into the perforations 7^a of the disk 7. 55 Depending upon the number of tablets, pills, or the like it is desired to fill into a receptacle X, the disk 7 will have so many holes or perforations, that is to say, should it be desired to pack, say, fifty tablets in a bottle 60 X, the disk 7 will have fifty perforations therein to accommodate and deliver to said receptacle fifty tablets. It will be seen that disks 7, as shown in Figs. 9 and 10, may be made with various numbers and sizes of 65 perforations to accommodate different sizes

and numbers of tablets to be packed in the receptacle, each perforation being large enough to accommodate and deliver one of the certain kind or size of tablet, pill, or other article, but not large enough to accommodate or deliver two such tablets, pills, or other article. It will also be plain that such disks 7 may be made in any number and are readily interchangeable in the machine, the disk 7 being easily removable after elevating 70 slide 61 and raising the deflector-plate 63.

In Fig. 1, the parts are shown as just finishing the filling of a bottle X with the tablets or pills carried and delivered by the perforations 7^a of disk 7 on one revolution 75 thereof and said non-perforated section 7^b of disk 7 is just beginning to cover and close said opening 9 in part 10 of table 5; the tappet 55 is also about to contact with projection 54 of rocking-lever 52 to actuate slide 80 48 to bring forward or shift, by means of dog 56, an empty receptacle or bottle X under chute 11. When the revolution of disk 7 is completed, said non-perforated section 7^b thereof will cover said opening 9, 85 during which time, tappet 55 having become engaged with rocking-lever 52, an empty receptacle is being automatically shifted under chute 11 by dog 56 on slide 48. The passage-way over said belt 32 and across 90 the front of front-plate 2 and under chute 11 having been regulated by the adjustment of plates 40 and 41 to accommodate a certain sized receptacle or bottle X, and chute 11 having been adjusted to coöperate with, 95 and to properly deliver the tablets or other articles into, said receptacle or bottle, the said receptacles or bottles X are fed on to belt 30, which carries the same into contact with or adjacent to slide 48. Now, when 100 said tappet 55 engages with said rocking-lever 52, said slide 48 and therewith dog 56 are actuated, against the tension of spring 53, and the dog 56, engaging the receptacle or bottle X brought adjacent to slide 48 by 105 belt 32, shifts the same across the front-plate 2 in the passage-way described under chute 11. On the continued revolution of ring 12 and disk 7, said non-perforated section 7^a is removed from above opening 9, 110 and, the perforations 7^a registering therewith during such continued revolution of disk 7, the tablets, pills, or the like carried therein fall therefrom through chute 11 into said receptacle. As soon as tappet 55 is 115 disengaged from rocking-lever 52, the slide 48 flies back to its normal or retracted position, due to the tension of spring 53, during which movement of slide 48, the dog 56 is flat against the outer surface of said slide, 120 so as, in returning to its outermost position, to pass and not upset the succeeding receptacle or bottle which has been brought forward by belt 32 adjacent to slide 48 and ready to be shifted by dog 56 under chute 125 130

11. After said dog 56 has thus passed said succeeding receptacle and has reached the end of slot 47, the tail-portion 57 thereof strikes against buffer 58 and throws dog 56 outwardly perpendicular to slide 48, in position to engage and shift the next succeeding receptacle under chute 11. As soon as disk 7 has made a revolution and emptied the tablets, pills, or the like therefrom into the receptacle under chute 11, said non-perforated section 7^b again closes opening 9, tappet 55 contacts with or strikes rocking-lever 52, slide 48 is actuated, and the next succeeding bottle or other receptacle is shifted by dog 56 under chute 11, ready to be filled on the continued revolution of disk 7 and the opening of opening 9 with a predetermined number of tablets, pills, or the like, of a certain kind or size depending upon the number and size of the perforations 7^a of disk 7, the said succeeding receptacle, on being shifted under chute 11, pushing from under chute 11 the preceding receptacle which has just been filled, and so on, the same series of operations being gone through with on each revolution of disk 7, the hopper 6 being kept filled with tablets, pills, or the like, and the bottles X or other receptacles being fed along belt 32 and intermittently shifted by dog 56 under chute 11 to be filled. As stated, as each bottle or other receptacle is shifted by dog 56 under chute 11 to be filled, it pushes the preceding bottle or receptacle out from under chute 11 and along said passage-way across the front of the machine, the receptacles or bottles being thus delivered on the work-table 30 to an operator, ready for sealing, wrapping, or otherwise.

40 The plates 40 and 41 may be readily and quickly adjusted to fit any sized receptacles, such as bottles, boxes, or other packages, so that there will be no play and such receptacles will be exactly placed under the chute 11, as before described, and chute 11 may be lowered or adjusted laterally along the forward part 10 of table 5, whereby the delivery-opening therein is brought above said receptacle and the escape of tablets prevented.

45 It may sometimes be desired to fill a receptacle with a larger number of tablets, pills, or the like than could be accommodated and delivered by a disk 7 on one revolution thereof. In such event, either the next succeeding receptacle is removed by the operator before it has been shifted by dog 56, the first receptacle being thus allowed to remain under chute 11 for two revolutions of said disk 7, and so on; or the bracket 28 and therewith table 30 and associated parts may be easily removed from front-plate 2 by unfastening thumb-screw 31, disconnecting the belt-connected pulleys 38 and 39, and disconnecting stud 49 from link 51, after which

the receptacle may be placed under chute 11 and allowed to remain there any length of time, depending upon the number of tablets it may be desired to place therein. And in order to facilitate the counting of the number of revolutions of disk 7 so that the proper predetermined number of tablets may be packed in such receptacle, I rotatably mount in a cut-out portion in the lower central part of the front surface of slide 61 a star-wheel 64, which is held in place in said cut-out portion by a plate 65, the outer surface of plate 65 being flush with the outer surface of slide 61. Star-wheel 64 has a dial on its outer surface containing or bearing usually the numerals 1 to 10 inclusive, one of which numerals is adapted to show through a small circular opening 66 in the plate 65 on each revolution of disk 7, to indicate to the operator the number of revolutions of disk 7, the projecting prong or tooth of said star-wheel, as shown particularly in Figs. 3 and 4, being actuated on each revolution of disk 7 by tappet 15 striking thereagainst and rotating said star-wheel to show the next succeeding numeral through opening 66. In this way, should it be desired to fill a receptacle with, say, 1000 tablets and the disk 7 then in the machine only had perforations to accommodate and deliver 50 tablets, the operator would know by watching said dial when twenty revolutions of said disk had been made and that 1000 tablets had then been packed into said receptacle. On the other hand, should it be desired to fill a receptacle with a smaller number of tablets, pills, or the like than there are perforations in the disk 7 then in the machine, to save the time required in removing said disk 7 then in the machine and inserting another disk 7 containing or bearing said smaller number of perforations, a deflector-plate 63 of larger diameter, as shown by dotted lines in Fig. 5, may be substituted for the deflector-plate of smaller diameter. Thus, should the disk 7 then in the machine have perforations for accommodating and delivering 50 tablets, but it was desired to pack only 25 tablets in a receptacle, it would only be necessary to remove the deflector-plate 63 and substitute a deflector-plate of larger diameter which would cover the inner series of perforations 7^a, leaving but 25 perforations to accommodate and deliver that number of tablets.

115 It is thus seen that by my machine the tablets, pills, or other articles are easily and automatically handled and counted and that the various receptacles to be filled therewith are intermittently and successively shifted into proper position to be filled, it being only necessary, as is obvious, to keep the machine supplied with the tablets, pills, or the like, and the receptacles fed to the machine, a great saving of time and labor being 120 125 130.

effected. Should it be at any time desired to clean hopper 6, I provide a small slide 67 in one side thereof for such purpose.

It is to be understood that while I have 5 herein described my machine as being used for counting and delivering tablets, pills, and the like, and filling receptacles therewith, my machine may be used for various other and different purposes, and also that 10 changes in the arrangement, construction, and combination of the several parts may be made and substituted for those herein shown and described without departing from the nature and principle of my invention.

15 Having thus described my invention, what I claim and desire to secure by Letters Patent is:

1. In a machine of the kind described, the combination with a hopper adapted to hold 20 a quantity of tablets, pills, or the like, of means adapted to intermittently feed receptacles to be filled into proper position relative to said hopper, perforated means rotatably mounted in said hopper, said perforated means being adapted to be continuously rotated and to deliver into each of said 25 receptacles a predetermined plurality of said tablets, pills, or the like, and mechanism for operating each of said respective means synchronically; substantially as described.

2. In a machine of the kind described, the combination with a hopper adapted to hold a quantity of tablets, pills, or the like, of perforated means rotatably mounted in said 35 hopper, said perforated means being adapted to be continuously rotated and, on each rotation thereof, to remove from said hopper and deliver to a receptacle to be filled a predetermined plurality of said tablets, pills, or the like, mechanism adapted to continuously rotate said perforated means, and means adapted to intermittently feed receptacles to be filled into proper position relative to said hopper on the rotation of said perforated means; substantially as described.

3. In a machine of the kind described, the combination with a hopper adapted to hold 50 a quantity of tablets, pills, or the like, of reciprocatory means adapted to shift receptacles to be filled into proper position relative to said hopper, perforated means rotatably mounted on said machine adapted to remove from said hopper and deliver to said 55 receptacles a number of said tablets, pills, or the like, mechanism for intermittently actuating said shifting means on the rotation of said perforated means, and mechanism for rotating said perforated means; substantially as described.

4. In a machine of the kind described, the combination with a hopper adapted to hold 60 a quantity of pills, tablets, or the like, of perforated means rotatably mounted in said 65 hopper and adapted to periodically remove

from said hopper and deliver to a receptacle to be filled a predetermined number of said tablets, pills, or the like, mechanism for rotating said perforated means, and reciprocatory means adapted to intermittently shift 70 receptacles to be filled into proper position relative to said hopper on the rotation of said perforated means; substantially as described.

5. In a machine of the kind described, the combination with a hopper adapted to hold a quantity of tablets, pills, or the like, of means having a plurality of perforations rotatably mounted in said hopper and adapted to remove from said hopper and deliver to 80 receptacles to be filled a predetermined plurality of said tablets, pills, or the like, mechanism adapted to rotate said means, and reciprocatory means adapted to intermittently shift 85 said receptacles to be filled into proper position relative to said hopper on the rotation of said perforated means; substantially as described.

6. In a machine of the kind described, the combination with a table having an opening 90 in its top, of a hopper mounted on said table to one side of said opening and adapted to contain a quantity of tablets, pills, or the like, perforated means rotatably mounted on said machine, said means being adapted to 95 be continuously rotated and to intermittently remove from said hopper and deliver to said opening a predetermined plurality of said tablets, pills, or the like, mechanism adapted to continuously rotate said perforated means, 100 and means adapted to intermittently feed receptacles to be filled into proper position relative to said opening on the rotation of said perforated means; substantially as described.

7. In a machine of the kind described, the combination with a table having an opening 105 in its top, of a hopper mounted on said table to one side of said opening and adapted to contain a quantity of tablets, pills, or the like, perforated means rotatably mounted on said machine and adapted to periodically remove from said hopper and deliver to 110 said opening a plurality of said tablets, pills, or the like, mechanism for rotating said 115 means, and reciprocatory means adapted to intermittently shift receptacles to be filled into proper position relative to said opening on the rotation of said perforated means; substantially as described.

8. In a machine of the kind described, the combination with a table having an opening in its top, of a hopper mounted on said table to one side of said opening and adapted to contain a quantity of tablets, pills, or the like, a perforated disk rotatably mounted on said table and having a non-perforated section, said disk being adapted to be continuously rotated within said hopper and over said table-opening, means adapted to 125 130

continuously rotate said disk, and means adapted to intermittently feed receptacles to be filled into proper position relative to said opening on the rotation of said perforated means; substantially as described.

9. In a machine of the kind described, the combination with a table having an opening in its top, of a hopper mounted on said table and adapted to contain a quantity of tablets, pills, or the like, a perforated disk rotatably mounted in said hopper and having a non-perforated section adapted to periodically cover said table-opening, means for rotating said disk, whereby on the rotation thereof said non-perforated section is periodically removed from over said opening and a number of said tablets, pills, or the like is periodically delivered through said opening, and reciprocatory means automatically operated on the rotation of said disk and adapted to intermittently feed receptacles to be filled into proper position relative to said opening; substantially as described.

10. In a machine of the kind described, the combination with a table having an opening in its top, of a hopper mounted on said table to one side of said opening and adapted to contain a quantity of tablets, pills, or the like, a disk rotatably mounted on said table and adapted to rotate within said hopper and over said table-opening, said disk being provided with a plurality of perforations for accommodating a plurality of said tablets, pills, or the like, and with a non-perforated section, means for rotating said disk, whereby said table-opening is periodically closed and the tablets, pills, or the like carried by said perforations are periodically delivered through said opening, and reciprocatory means adapted to intermittently feed receptacles to be filled into operative position relative to said opening on the closing thereof during the rotation of said disk; substantially as described.

11. In a machine of the kind described, the combination with a table having an opening in its top, of a hopper mounted thereon and adapted to contain a quantity of tablets, pills, or the like, a disk rotatably mounted on said table, said disk being provided with a plurality of perforations and with a non-perforated section and rotating within said hopper and over said table-opening, whereby on the rotation thereof said table-opening is periodically closed by said non-perforated section and said perforations periodically deliver to said opening a plurality of said tablets, pills, or the like, means adapted to rotate said disk, means adapted to feed receptacles to be filled beneath said table-opening, and reciprocatory means adapted to automatically shift said receptacles under said opening on the closing thereof; substantially as described.

12. In a machine of the kind described,

the combination with a table having an opening in its top, of a hopper mounted on said table to one side of said opening and adapted to contain a quantity of tablets, pills, or the like, a disk rotatably mounted on said table and adapted to rotate within said hopper and over said table-opening, said disk being provided with a plurality of perforations for accommodating a plurality of said tablets, pills, or the like, and with a non-perforated section, means for rotating said disk, whereby on each revolution thereof said table-opening is periodically closed by said non-perforated section and the tablets, pills, or the like carried by said perforations are periodically delivered to said table-opening, means adapted to feed to said table receptacles to be filled, and reciprocatory means adapted to successively shift under said table-opening on the closing thereof during the rotation of said disk said receptacles to be filled; substantially as described.

13. In a machine of the kind described, the combination with a frame having an opening in its top member, of a hopper mounted on said frame and adapted to hold a quantity of tablets, pills, or the like, a beveled rack rotatably mounted on said frame, a perforated disk adapted to rotate within said hopper and over said frame-opening, a stud on said rack adapted to engage said disk to cause the same to rotate with said rack, a shaft meshing with said rack, and means adapted to rotate said shaft; substantially as described.

14. In a machine of the kind described, the combination with a frame having an opening in its top member, of a hopper mounted on said frame to one side of said opening and adapted to hold a quantity of tablets, pills, or the like, a disk having a plurality of perforations and a non-perforated section, said disk being adapted to rotate within said hopper and over said frame-opening, whereby said frame-opening is intermittently closed and tablets, pills, or the like are intermittently delivered to said frame-opening, a beveled rack rotatably mounted on said frame, a stud on said rack adapted to removably engage said disk to cause the same to rotate with said rack, a rotatable shaft meshing with said rack, and means adapted to rotate said shaft; substantially as described.

15. In a machine of the kind described, the combination with a hopper adapted to hold a quantity of tablets, pills, or the like, of perforated means adapted to intermittently remove from said hopper a plurality of said tablets, pills, or the like, means adapted to actuate said perforated means, reciprocatory means adapted during the actuation of said perforated means to intermittently shift into operative position relative to said hopper receptacles to be filled, and

means adapted to feed said receptacles to said reciprocatory means; substantially as described.

16. In a machine of the kind described, the combination with a hopper adapted to hold a quantity of tablets, pills, or the like, of rotatable perforated means adapted to intermittently remove from said hopper a plurality of said tablets, pills, or the like, means adapted to rotate said perforated means, reciprocatory means adapted during the rotation of said perforated means to intermittently shift into operative position relative to said hopper on the rotation of said perforated means receptacles to be filled, and means adapted to feed said receptacles to said reciprocatory means; substantially as described.

17. In a machine of the kind described, the combination with a frame, of a hopper thereon adapted to hold a quantity of tablets, pills, or the like, rotatable perforated means mounted on said frame and adapted to intermittently remove from said hopper a plurality of said tablets, pills, or the like, means adapted to rotate said perforated means, a reciprocatory device adapted during the rotation of said perforated means to intermittently shift receptacles to be filled into operative position relative to said hopper and perforated means, and a belt-conveyer adapted to feed said receptacles to said reciprocatory device; substantially as described.

18. In a machine of the kind described, the combination with a frame having an opening in its top member, of a hopper on said frame adapted to hold tablets, pills, or the like, means rotatably mounted on said frame and adapted to intermittently remove from said hopper and deliver through said frame-opening a number of said tablets, pills, or the like, mechanism adapted to rotate said means, a slide mounted on said frame, a dog on said slide adapted to engage receptacles to be filled, and means adapted to intermittently actuate said slide on the rotation of said rotatable means, whereby said receptacles to be filled are intermittently shifted into operative position relative to said frame-opening; substantially as described.

19. In a machine of the kind described, the combination with a frame having an opening in its top member, of a hopper on said frame adapted to hold tablets, pills, or the like, means on said frame adapted to rotate within said hopper and over said frame-opening and to remove from said hopper and deliver to said opening a number of said tablets, pills, or the like, a rotatable gear on which said means is mounted, mechanism adapted to rotate said gear, a slide on said frame, a dog on said slide adapted to engage a receptacle to be filled, a rocking-lever on said frame, a link connecting said slide to said rocking-lever, a tappet on said gear

adapted to intermittently engage with said rocking-lever on the rotation of said gear, whereby said dog is intermittently actuated to shift a receptacle to be filled into operative position relative to said frame-opening, a spring adapted to normally hold said rocking-lever in position to be engaged by said tappet, and a conveyer adapted to feed to said dog receptacles to be filled; substantially as described.

20. In a machine of the kind described, the combination with a frame, of a gear rotatably mounted thereon, mechanism adapted to rotate said gear, a slide on said frame, a dog on said slide, a rocking-lever on said frame, a link connecting one end of said rocking-lever to said slide, a tappet on said gear adapted to intermittently engage the other end of said rocking-lever on the rotation of said gear, whereby said slide and dog are intermittently reciprocated on the rotation of said gear, and a spring connected to said frame and to said rocking-lever and adapted to normally hold said rocking-lever in position to be engaged by said tappet; substantially as described.

21. In a machine of the kind described, the combination with a table having an opening in its top, of a hopper mounted on said table to one side of said opening and adapted to hold a quantity of tablets, pills, or the like, a chute adjustably attached to said table under said opening, a disk provided with a plurality of perforations rotatably mounted in said hopper and adapted to intermittently remove therefrom and deliver to said chute a plurality of said tablets, pills, or the like, mechanism adapted to rotate said disk, and reciprocatory mechanism adapted to intermittently shift receptacles to be filled under said chute during the rotation of said disk; substantially as described.

22. In a machine of the kind described, the combination with a hopper adapted to hold tablets, pills, or the like, of a rotatable disk adapted to periodically remove from said hopper a number of said tablets, pills, or the like, said disk being removably mounted in said hopper, a plate adapted to removably hold said disk in position, and means adapted to rotate said disk; substantially as described.

23. In a machine of the kind described, the combination with a hopper adapted to hold tablets, pills, or the like, of a rotatable disk adapted to periodically remove from said hopper a number of said tablets, pills, or the like, said disk being removably mounted in said hopper, a deflector plate adapted to removably hold said disk in position, and mechanism adapted to rotate said disk; substantially as described.

24. In a machine of the kind described, the combination with a hopper adapted to hold tablets, pills, or the like, of a disk pro-

vided with a plurality of perforations rotatably mounted in the bottom of said hopper and adapted to periodically remove therefrom a number of said tablets, pills, or the like, mechanism adapted to rotate said disk, and interchangeable deflectors of various diameters adapted to be placed over said disk, whereby the effective capacity of said disk may be varied; substantially as described.

25. In a machine of the kind described, the combination with a frame, of a hopper thereon adapted to hold tablets, pills, or the like and having an opening in one side thereof, a disk rotatably mounted in said hopper and adapted to project through said opening in the side thereof, said disk having a plurality of perforations adapted to receive a number of said tablets, pills, or the like, mechanism adapted to rotate said disk, whereby said perforations are successively carried outside said hopper, and plates of various diameters adapted to be placed over said disk, whereby the effective capacity of said disk may be varied; substantially as described.

26. In a machine of the kind described, the combination with a frame having an opening in its top member, of a hopper on said frame adapted to hold tablets, pills, or the like, means rotatably mounted on said frame and adapted to remove from said hopper and deliver to said opening a predetermined number of said tablets, pills, or the like, means adapted to rotate said rotatably-mounted means, a table on said frame adapt-

ed to support receptacles to be filled, means on said table adapted to form an adjustable passage-way thereon for said receptacles, and means adapted to intermittently feed said receptacles along said passage-way into operative position relative to said opening during the rotation of said rotatably mounted means; substantially as described.

27. In a machine of the kind described, the combination with a frame having an opening in its top member, of a hopper on said frame adapted to hold tablets, pills, or the like, means rotatably mounted on said frame and adapted to remove from said hopper and deliver to said opening a predetermined number of said tablets, pills, or the like, means adapted to rotate said rotatably-mounted means, a table on said frame adapted to support receptacles to be filled, a plate 55 adjustably arranged on said table and adapted to form an adjustable passage-way thereon for said receptacles, means adapted to intermittently shift receptacles along said passage-way into operative position relative to 60 said opening during the rotation of said rotatably mounted means, and means adapted to feed receptacles to said shifting means; substantially as described.

In testimony whereof, I have signed my 65 name to this specification, in the presence of two subscribing witnesses.

EDWARD E. KALLENBACH.
